UNITED STATES PATENT OFFICE.

JAMES EDWARD STONE, OF KIDDERMINSTER, ENGLAND, ASSIGNOR TO ARNOLD CONSTABLE & CO., OF NEW YORK CITY.

DESIGN FOR A CARPET-PATTERN.

Specification forming part of Design No. 5,402, dated December 5, 1871.

To all whom it may concern:

Be it known that I, JAMES EDWARD STONE, of Kidderminster, in the county of Worcester, in England, have invented a new and original Design for a Carpet; and I do hereby declare that the following is a full, clear, and exact description thereof, which will enable others skilled in the art to make and use the same, reference being had to the accompanying photographic illustration forming part of this specification.

In the drawing, a a and c c represent corner-edge figures; b b, middle-edge figures; and d e, main and intermediate figures.

The nature of my invention is fully represented in the accompanying photographic illustration, to which reference is made.

I claim as my invention—
The design for a carpet, as shown.

JAMES EDWARD STONE.
